UNITED STATES PATENT OFFICE.

CHARLES L. SEBRING AND EDWARD BROOKS, OF SEBRING, OHIO, ASSIGNEES TO THE SEBRING POTTERY COMPANY, OF SEBRING, OHIO, A CORPORATION OF OHIO.

DESIGN FOR A COVERED DISH.

Application filed November 17, 1923. Serial No. 7,801. Term of patent 7 years.

To all whom it may concern:

Be it known that we, CHARLES L. SEBRING and EDWARD BROOKS, both citizens of the United States, residing at Sebring, in the county of Mahoning and State of Ohio, have invented a new, original, and ornamental Design for Covered Dish, of which the following is a specification, reference being had to the accompanying drawing, forming part hereof.

In the drawings:

Fig. 2, a side elevation of the same.

We claim:

The ornamental design for a covered dish, substantially as shown.

CHARLES L. SEBRING.
ED BROOKS.
